UNITED STATES PATENT OFFICE.

FRANCIS A. STAFFORD, OF FULTON, NEW YORK, ASSIGNOR TO THE HUNTER ARMS COMPANY INC., OF FULTON, NEW YORK, A CORPORATION OF NEW YORK.

FIREARM.

1,387,207.

Specification of Letters Patent.

Patented Aug. 9, 1921.

Application filed June 8, 1917. Serial No. 173,539.

To all whom it may concern:

Be it known that I, FRANCIS A. STAFFORD, a citizen of the United States, and a resident of Fulton, in the county of Oswego 5 and State of New York, have invented a certain new and useful Firearm, of which the following is a specification.

This invention has for its object a particularly simple and efficient arrangement 10 and construction of the firing mechanism and barrel locking mechanism; and the invention consists in the combinations and constructions hereinafter set forth and claimed.

In describing this invention reference is 15 had to the accompanying drawings, in which like characters designate corresponding parts in all the views.

Figure 1 is a longitudinal sectional view 20 of a fire arm embodying my invention, parts being omitted.

Figs. 2 and 3 are, respectively, front and rear elevations of the frame, partly in section.

Fig. 4 is an inverted plan view of the 25 frame, partly in section and parts being omitted.

Fig. 5 is a fragmentary elevation taken from the left side of the frame and partly in section.

Fig. 6 is a fragmentary sectional view on line 6—6, Fig. 2.

Fig. 7 is a fragmentary sectional view on line 7—7, Fig. 3.

Figs. 8 and 9 are, respectively, front elevation and plan of the locking bolt.

1 designates the frame which includes the breech block 2. 3 is the barrel which, in this form of my invention, is hinged at 4 to the frame as in a break down shot gun. 5 40 is the fore-piece.

The breech block is formed with a bearing 6 which opens through its rear face and with a slot 7 opening through its top and into the cylindrical bearing, the bearing usually extending lengthwise of the gun and being nearly horizontal, and the slot extending lengthwise of said bearing and receiving a rearwardly extending lug 8 on the barrel.

9 is a rotating bolt journaled in the bearing 6 and having means as arc-shaped hooks for interlocking with the lug 8, it being here shown as a cylinder having a lengthwise slot 10 and a circumferential slot 11 intersecting the slot 10, these two slots forming arc-shaped hooks 12, 13 which interlock with

the lug 8. The hook 12 moves through a slot 14 in the lug 8 and the hook 13 moves over a rearwardly extending shoulder 17 on the end of the lug. When the bolt is turned to its locked position, the hooks extend 60 through the slot 14 and over the shoulder 17, respectively, and hold the barrel in its closed position.

The bolt is actuated by a lock or thumb lever 18, and is formed with a shank 19 extending through the upper tang 20 of the frame and having a connection with the bolt to rotate the same. This connection is here shown as a radially extending pin 21 mounted on the shank 19 and extending into and 65 slidably engaging the walls of an eccentrically located opening in the rear end of the bolt 9. This pin 21 is provided with a fork 22 at its rear end which embraces the shank 19 and which is connected thereto by a transverse pivot 23, the pin 21 having a slight 70 pivotal movement during the rocking of the bolt.

The shank 19 extends vertically into the frame and terminates between the top and 80 bottom of the frame and usually above the central part of the frame, it being here shown as supported at its lower end on a shelf 24 extending rearwardly from the breech block 2 above the center thereof, and 85 secured thereto by screws 25 extending through downwardly extending flanges on the shelf and into the breech block.

A spring normally tends to hold the thumb lever in its normal position, that is, 90 in its position assumed when the locking bolt 9 is in its locked position.

As here shown, the shank is provided with a radially extending shoulder 26 at its lower end contiguous to the shelf 24, which is 95 acted upon by a spring-pressed pin 27 arranged in the lengthwise bore 28 in the breech block. The shoulder 26 is here shown as separable from the shank and is in the form of a ratchet tooth on a disk 100 mounted on a square axial stud 26^a on the lower end of the shank.

A fastening screw 29 extends vertically 105 upwardly through the shelf 24 and threads into the stud.

The locking bolt is held in its unlocked position by means of a spring-pressed latch 31 arranged in an obliquely extending bore 32 in the breech block, this bore being also arranged radially relatively to the cylin- 110

drical bearing 6, the latch extending through a cut out 6^a in the front face of the rotating bolt and into the path of the lug 8, the latch also having a shoulder 33 for 5 entering a notch 34 in the lower side of the rotating bolt, the notch 34 coming into position to receive the latch 31 when the bolt 9 is in its unlocked position. The cut out 6^a is long enough to permit partial rotation 10 of the bolt and the end walls thereof limits the movement of the rotating bolt.

When the spring-pressed latch is in its locked position, its upper end is in the path of the barrel lug 8 and as the barrel moves 15 to its closed position, this lug engages the upper end of the latch and depresses the latch to remove its locking shoulder 33 out of engagement with the notch 34, thus permitting the spring of the thumb lever 18 to 20 return the thumb lever 18 to its closed position and thereby move the bolt 9 to its locked position.

35 designates the hammer forming part of the firing mechanism, this hammer being 25 located centrally of the frame beneath the shelf 24 and engaging directly with the firing pin 36 located centrally of the breech block and extending in a vertical plane rearwardly therefrom instead of obliquely 30 therefrom. 35^a is the hammer spring arranged in a lengthwise bore located centrally of the breech block and acting on a plunger 35^b coacting with the tail of the hammer.

35 As shown in Fig. 5 the firing pin 36 moves in a bore 37 in the breech block and has a head 38 at its rear end movable in a countersink 39 at the rear end of the bore 37, the head coacting at its rear side with the 40 wall of a recess 40 in the shelf 24 and at its front side with the shoulder 41 formed by the countersink 39 at the rear of the bore 37.

The hammer, hammer spring and the 45 firing pin are thus located centrally of the gun, and, owing to the shelf 24 and the manner of supporting the thumb lever, said hammer is centrally located, in a particularly simple and efficient manner, in such position that it can coact with the firing pin.

50 The hammer 35 is here shown as provided with an offset or laterally extending arm 43 for coacting with the cocking mechanism

operating during the movement downwardly of the barrel 3 on its hinge 4. This cocking mechanism, as here shown, includes a 55 rock shaft 44, Fig. 4, extending lengthwise of the breech block below and at one side of the center of the barrel and is provided with eccentric shoulders or rock arms 45, 46 at its front and rear ends.

The rock arm 45 coacts with a suitable shoulder 47 on the fore-piece during the breaking of the gun, as will be understood by those skilled in the art, and the rock arm 46 presses against a lug or shoulder 48 on 65 the offset or laterally extending arm 43. During the breaking of the gun the shaft 44 is rocked and the arm 46 thereof bears against the offset of the centrally located hammer and cocks the hammer.

70 What I claim is:

1. In a gun, a frame including a breech block, a barrel hinged to the frame, a shelf projecting from the breech block centrally thereof and between the top and the bottom of the frame, a lock for holding the barrel in its normal position, a thumb lever carried on the top of the frame and having its shank engaged at its lower end with the shelf, and firing mechanism including a 80 hammer located directly below the shelf centrally of the frame, substantially as and for the purpose specified.

2. In a gun, a frame including a breech block, a barrel hinged to the frame, the 85 breech block having a horizontal shelf between its upper and lower sides and also having a lock opening for the barrel above the shelf, a thumb lever having a shank extending downwardly through the top of the 90 frame to the rear of the opening for the lock and coacting with the lock, the lower end of the shank being engaged with the shelf, a firing pin movable in the breech block below the shelf, and a hammer movable directly beneath the shelf into and out of engagement with the firing pin, substantially as and for the purpose described.

95 In testimony whereof, I have hereunto signed my name, at Fulton, in the county 100 of Oswego, and State of New York, this 31st day of May, 1917.

FRANCIS A. STAFFORD.
